UNITED STATES PATENT OFFICE.

DANIEL J. GESSLER, OF SAN FRANCISCO, CALIFORNIA, ASSIGNOR, BY MESNE ASSIGNMENTS, TO UNIVERSAL SPECIALTY COMPANY, A COPARTNERSHIP CONSISTING OF LILLIAN V. GESSLER, ALBERT J. BROWN, WILLIAM KLEIN, REED M. CLARKE, AND ALVIN GERLACK.

DESIGN FOR A COMBINED ELECTRIC HEATER AND LAMP STAND.

Application filed April 2, 1923. Serial No. 5,662. Term of patent 3½ years.

To all whom it may concern:

Be it known that I, DANIEL J. GESSLER, a citizen of the United States, residing at the city and county of San Francisco and State of California, have invented a new, original, and ornamental Design for Combined Electric Heater and Lamp Stand, of which the following is a specification, reference being had to the accompanying drawing, forming part thereof.

The figure is a perspective view of a combined electric heater and lamp stand, showing my new design.

I claim:

The ornamental design for a combined electric heater and lamp stand, as shown.

DANIEL J. GESSLER.
